Primary Examiner — Angela J Lee(74) *Attorney, Agent, or Firm* — Saidman DesignLaw Group, LLC(57) **CLAIM**

The ornamental design for an electronic device with connector, as shown and described.

DESCRIPTION

FIG. 1 is a perspective view of an electronic device with connector showing our new design; and, FIG. 2 is a front view thereof.

The dashed broken lines illustrate portions of the electronic device with connector that form no part of the claimed design.

The dot-dot-dash broken lines illustrate boundaries; the dot-dot-dash lines themselves form no part of the claimed design.

The gray shading in FIGS. 1-2 illustrates a metallic surface.
